(57) **CLAIM**

The ornamental design for a laboratory device display screen with graphical user interface, as shown and described.

DESCRIPTION

FIG. 1 shows a laboratory device display screen showing the first image in a sequence; and,

FIG. 2 shows a second image thereof.

The appearance of the transitional image sequentially transitions between the images shown in FIGS. 1 and 2. The process or period in which one image transitions to another image forms no part of the claimed design.
